CLAIM

The ornamental design for a surgical arm with tray as shown and described.

DESCRIPTION

FIG. 1 is top perspective view of a surgical arm with tray showing my new claimed design;

FIG. 2 is a right-side elevational view thereof;

FIG. 3 is a left-side elevational view thereof;

FIG. 4 is a front elevational view thereof;

FIG. 5 is a back elevational view thereof;

FIG. 6 is a top plan view thereof;

FIG. 7 is a bottom plan view thereof;

FIG. 8 is a bottom perspective view thereof

FIG. 9 is a top plan view in accordance with a first embodiment of the surgical arm with tray of indeterminate width shown in FIG. 1; and,

FIG. 10 is a top plan view in accordance with a second embodiment thereof.

The evenly spaced broken lines shown in FIGS. 1-10 depict portions of the surgical arm with tray that form no part of the claimed design. The additional dash-dot-dash broken lines in FIGS. 1 and 4-8 represent symbolic breaks of indeterminate width and form no part of the claim thereof.
